UNITED STATES PATENT OFFICE.

GODFREY H. LASAR, OF ST. LOUIS, MISSOURI.

TYPE-WRITING MACHINE.

SPECIFICATION forming part of Letters Patent No. 415,523, dated November 19, 1889.

Application filed October 11, 1888. Serial No. 215,904. (No model.)

To all whom it may concern:

Be it known that I, GODFREY H. LASAR, a citizen of the United States, residing at the city of St. Louis, in the State of Missouri, have invented a certain new and useful Improvement in Type-Writing Machines, of which the following is a full, clear, and exact description, reference being had to the accompanying drawings, forming part of this specification, and in which—

Figure 1 is a front view of the carriage mechanism of my improved machine, a portion of the front rail being omitted to exhibit the carriage-spring. Fig. 2 is a rear view of same. Fig. 3 is a top view thereof in the position shown in Fig. 2. Fig. 4 is a section on line 4 4, Fig. 2, looking in the direction of the arrows. Fig. 5 is a top view of the escapement of the machine. Fig. 6 is an enlarged front view of the escapement. Fig. 7 is a detail perspective view of same. Fig. 8 is an enlarged detail top view showing one end of the carriage. Fig. 9 is a perspective view of same. Fig. 10 is a transverse vertical section on line 10 10, Fig. 8, looking in the direction of the arrows. Fig. 11 is an elevation showing the other end of the carriage from that shown in Figs. 8, 9, and 10. Fig. 12 is a side elevation of the escapement mechanism, showing a modification in the means for returning the dogs to normal position.

This invention relates to certain improvements in type-writing machines; and it consists in features of novelty hereinafter fully described, and pointed out in the claims.

Referring to the drawings, A represents the part of the main frame of a type-writer that supports the carriage mechanism. This frame is provided with an upward extension A', into which is dovetailed a downwardly-extending projection B' of a track-frame B. To the front of the track-frame are journaled the grooved rollers B², upon which the front portion of the carriage is supported and upon which it moves back and forth, the carriage having a front rail C', which rests and works in the rollers B². At the rear side of the track-frame B are journaled the grooved rollers B³, on which the rear angular rail C³ of the carriage is supported. The carriage C is provided with a rack C², in which engages a

fixed dog D' and a pivoted dog D² of the escapement. Both of these dogs are secured to a vertically-movable plate D, which is dovetailed into the projection B' of the frame B, 55 and the plate is connected by means of a pitman D³ to an operating-key D⁴. Each time the key D⁴ is operated or each time one of the keys of the machine is operated the escapement-plate D is pulled down, disengaging the pivoted dog D² from the teeth in the rack and bringing the fixed dog D' into engagement. The rod or pitman D³ is connected to the escapement-plate D (see Figs. 2, 4, and 6) by a thumb-screw E, passing through a slot E' in 65 the pitman D³, so as to permit of an adjustment of the pitman D³ to change, if necessary, the vertical movement of the escapement-plate. The fixed dog D' is arranged over the rack, as shown in Figs. 4 and 6, so as to move 70 vertically into engagement with the rack when the escapement is pulled down, and the pivoted dog, when the escapement is pulled down, moves vertically out of engagement with the rack. This dog is pivoted or secured to a pin 75 tle D⁵, passing through a projection D⁶, secured to or formed upon the plate D, and when in engagement with the rack it bears against a lug D⁷ on the extension or projection D⁶. (See dotted lines, Fig. 5.) When 80 the escapement is pulled down, this dog is moved into the position shown in full lines in Fig. 5 by means of a spring D⁸, adjusted to throw the dog the distance of a notch or tooth, secured to the projection D⁶ or to any 85 other fixed part of the escapement, and entering a perforation D⁹ in the dog, or it may be secured to the dog in any other suitable manner. Now, when the escapement is pulled down, this spring D⁸ moves the dog D² back 90 away from the lug D⁷ the distance of one notch or tooth in the rack, so that when the escapement moves upward again the dog will engage the next tooth to that previously occupied by it, and the carriage will then be 95 moved forward the distance of one tooth (it being understood that the fixed dog moves out of engagement with the teeth of the rack as the pivoted dog moves into engagement) under the influence of a spring F, and the 100 movement of the carriage is checked or stopped by the dog D² coming against the lug

D⁷. Thus each time the escapement moves downward the carriage is held from movement by the fixed dog, and each time the escapement moves upward the carriage is allowed to move forward the distance of one notch or tooth by the action of the pivoted dog.

In case it is desired to run the carriage back and forth without printing, it can be done by forcing the pivoted dog (without lowering the escapement) out of engagement with the teeth of the rack by forcing it into the position shown in dotted lines, Fig. 7, where it comes against a lug D¹⁰ on the projection D⁶, and into this position it is forced by means of a push-rod D¹¹, upheld at its inner end by the lug D⁷, through which it passes, and supported at its outer end by a lug or bracket D¹², secured to or formed upon the frame B, (see Fig. 2,) there being a spring D¹³, located between the bracket D¹² and the head D¹⁴ of the push-rod, for the purpose of holding the push-rod back out of engagement with the dog D², except when it is forced inward to disengage the dog from the teeth of the rack, as stated.

The rod D¹¹ is sufficiently flexible to bend slightly at its inner end to permit it to follow the movement of the plate, the hole in the lug D⁷ for the inner end of the rod being larger than the rod to allow for free play of the inner end of the rod.

When the escapement has been pulled down and the pressure has been removed from the operating-key, the escapement moves up automatically under the influence of a spring D¹⁵, (see Fig. 6,) or it may be moved upward under the influence of a spring-frame arrangement, as shown in Fig. 12, where D¹⁷ is a rod connected to the projection D⁶ of the plate and to the cross-bar or rod D²⁰ of a frame D¹⁶, extending beneath the key-levers D¹⁸. The frame is hinged to the pivot-bar D¹⁹ of the key-levers and provided with a lug D²¹, pressed downward by a spring D²², surrounding a pin D²³ beneath the pin's head D²⁴, the pin being secured to the base D²⁵, as usual. The spring F is connected to the carriage at F' and is in form quite similar to the spring used for the same purpose on the well-known Remington machine; but instead of being located at one end of the carriage it is located in the center and is pivoted by means of a bolt or pin F² to the front side of the projection B' of the frame B. By thus providing a means for the support of and by thus locating the spring at the center of the track-frame a neater and more compact arrangement is had. The spring, as stated, being secured to the front side of the projection B', it does not interfere with the connection of the frames B and A, nor does it interfere with the operation of the escapement nor the adjustment of the carriage up or down.

G represents a movable paper shield or guide, which acts also to hold the paper

against the roller C³ of the carriage, it being capable of being moved from the position shown in full lines to the position shown in dotted lines for the purpose of inserting the sheet of paper to be printed upon. It is thus moved by a rock-shaft H, journaled in suitable supports H', by which it is secured to the ends C⁴ of the carriage. It is provided with one or more notched projections H², (see Fig. 4,) which receive lugs or projections G', depending from the bottom of the guide or shield G. It will thus be seen that as the shaft H is rocked back and forth the shield or guide G will be moved to and from the roller C³ of the carriage. The shaft is thus rocked by means of a lever I, secured thereto, and which is provided with a pawl or dog I', engaging teeth or notches I² in one of the end pieces C⁴ of the carriage, the pawl being held into engagement with the teeth by a spring I³.

When all or part of one line has been written and it is desired to run the carriage back for a fresh line, it may be done by means of a bell-crank lever J, pivoted at J' to a plate J², secured to one of the end pieces of the carriage. As the carriage is thus run back by means of this bell-crank lever the paper-roller C³ of the carriage is turned to move the paper the distance of one line by means of a spring-dog J³, engaging a ratchet-wheel J⁴ on one end of the roller, (see Figs. 8, 9, and 10,) the dog being moved inward toward the roller each time the bell-crank lever J turns outward on its pivot J', which it does each time pressure is applied to run the carriage back. The inward movement of the dog (and consequently the movement of the roller) is limited by the outer end of the bell-crank lever J coming against a lug or projection J⁵ on the plate J². (See Figs. 1, 3, 8, and 9.) The backward movement of the dog (or its movement in a direction away from the roller) is limited by the outer end of the lever J coming against a pivoted block L, as shown in Figs. 8 and 9, so that the dog is merely allowed to move back far enough to engage the next tooth of the ratchet-wheel to that last occupied by it; but in case it should be desired to have the dog engage the second tooth behind that last occupied by it, so as to give a double space on the sheet, it may be done by throwing the pivoted block L up, so as not to be engaged by the end of the lever J, and the lever will then come against a lug or projection J⁶ on the plate J², and then the next time the lever J is operated the roller will be turned the required distance for a double space.

In case it is desired to turn the roller backward the dog J³ may be disengaged from the ratchet-wheel by means of a push-pin J⁷, located over the dog and guided and held in a projection J⁸, secured to this end piece of the carriage.

If it should be desired to change the relative positions of the frames A and B, it may be done by a screw M, held in a lug M', formed upon or secured to the projection A' of the

frame A, and which screws into a lug M², formed upon or secured to the projection B', and this screw is provided with a wheel M³, or by other suitable means by which it may be turned.

The principal object in making the carriage vertically adjustable is to retain, in making manifold copies, the same striking center vertically for the types as when single copies are being made. Thus, in case a machine is constructed in such a manner that the type-levers have an upward stroke, the carriage would (when making manifold copies) be elevated or raised slightly by turning the wheel M³, so that the type-bars would move the same distance to print with a number of sheets in as with a single sheet. On the other hand, if the type-bars have a downward stroke or movement and manifold copies are being made, the carriage will be moved downward slightly to retain the same striking center for the type.

I am aware of Letters Patent of the United States numbered 344,933, and dated July 6, 1886, and do not claim, broadly, the combination, with a carriage having a rack, of a sliding plate provided with a fixed dog and a movable dog, nor the combination of a carriage provided with a rack, a sliding plate provided with a fixed dog projecting over the rack, and a movable dog with means for limiting the movement of the movable dog and reciprocating the plate.

I claim as my invention—

1. An escapement for type-writers, consisting of a sliding plate D, having a projection D⁶, a fixed dog D', pivoted dog D², secured to the projection, having perforation D⁹, lug D⁷, and a spring D⁸, secured to the plate and to the pivoted dog.

2. The combination, with a carriage, of the main frame A, formed with an upward projection A' and a laterally-projecting lug M', the track-frame B, formed with a downward projection B', sliding in the projection of the

main frame and having a laterally-projecting lug M², and the adjusting-screw M³, working in the lugs.

3. The combination, with a carriage having a rack, of a sliding plate provided with a fixed dog and a movable dog, means, substantially as described, for reciprocating the plate, lugs or projections on the plate for limiting the movement of the movable dog in either direction, and a push-rod for disengaging the movable dog from the rack.

4. The combination of a carriage having a paper-roller, a movable guide or shield having a downwardly-projecting outer portion and an upwardly-projecting inner portion, and a lever and pawl-and-ratchet mechanism, substantially as described, for adjusting the guide or shield.

5. In a type-writer, in combination with the paper-roller, a movable shield provided with a projection, a rock-shaft, lugs on the rock-shaft engaging the projection on the shield, lever secured to the rock-shaft, and pawl on the lever for engaging notches on one of the end pieces of the carriage, substantially as and for the purpose set forth.

6. In a type-writer, in combination with a paper-roller provided with a ratchet-wheel, a bell-crank lever J, having a spring-dog J³ engaging the ratchet-wheel, a support J², to which the bell-crank lever is pivoted, having outer stop J⁵ and inner stop J⁶, and a hinged stop L, substantially as described.

7. In a type-writer, in combination with a paper-roller provided with a ratchet-wheel, a spring-dog engaging the ratchet-wheel, a pivoted bell-crank lever to which the dog is secured and by which it is operated, and a push-pin located over the dog and by which it may be disengaged from the ratchet-wheel, substantially as and for the purpose set forth.

GODFREY H. LASAR.
